[57] CLAIM

The ornamental design for a slipper, substantially as
shown and described.

DESCRIPTION

FIG. 1 is a front perspective view of a slipper showing
my new design;

FIG. 2 is a top plan view thereof;

FIG. 3 is a right side elevational view thereof as seen
from the front of the slipper;

FIG. 4 is a front elevational view thereof;

FIG. 5 is a cross-sectional view of the upper as taken
from line 5—5 of FIG. 2;

FIG. 6 is a cross-sectional view of the sole as taken from
line 6—6 of FIG. 2.
